UNITED STATES PATENT OFFICE

165,584

TABLE OR SIMILAR ARTICLE

Elster H. Johnson, San Francisco, Calif.

Application January 23, 1951, Serial No. 13,918

Term of patent 3½ years

(Cl. D33—14)

To all whom it may concern:

Be it known that I, Elster H. Johnson, a citizen of the United States of America, residing in the city and county of San Francisco, and State of California, have invented a new, original, and ornamental Design for a Table or Similar Article of which the following is a specification, reference being made to the accompanying drawing, forming a part thereof:

Fig. 1 is a perspective view of a table or similar article, showing my new design.

Fig. 2 is a top plan view of Fig. 1; and

Fig. 3 is a side elevation of Fig. 1.

I claim:

The ornamental design for a table or similar article, substantially as shown.

ELSTER H. JOHNSON.
